UNITED STATES PATENT OFFICE

93,192

DESIGN FOR A TOY

Ladislas Turchányi, Sashalom, near Budapest, Hungary, assignor to Magyar Ruggyantáru Gyár Részvénnytársaság, Budapest, Hungary, a corporation of Hungary

Application April 3, 1934, Serial No. 51,301

Term of patent 7 years

To all whom it may concern:

Be it known that I, LADISLAS TURCHÁNYI, a citizen of the Kingdom of Hungary, residing in the village of Sashalom, near the city of Budapest, Hungary, have invented a new, original, and ornamental Design for Toy, of which the following is a specification, reference being had to the accompanying drawing, forming a part thereof.

I claim:

The ornamental design for a toy substantially as shown.

LADISLAS TURCHÁNYI.
